UNITED STATES PATENT OFFICE.

ELTON W. McCASLIN, OF CHICAGO, ILLINOIS, ASSIGNOR TO THE MORGAN & WRIGHT, OF SAME PLACE.

DESIGN FOR A VALVE-CASE FOR PNEUMATIC TIRES.

SPECIFICATION forming part of Design No. 33,301, dated October 2, 1900.

Application filed September 22, 1899. Serial No. 731,355. Term of patent 14 years.

To all whom it may concern:

Be it known that I, ELTON W. McCASLIN, a citizen of the United States, residing at Chicago, in the county of Cook and State of Illinois, have invented and produced a new and original Design for a Valve-Casing for Pneumatic Tires, of which the following is a specification, reference being had to the accompanying drawings, forming part thereof.

10 In said drawings, Figure 1 shows the elastic valve-casing in perspective. Fig. 2 shows the same in side elevation.

15 The valve-casing shown is formed with a tubular stem or body A, having at one end a spread-out flattened base B and having at

its opposite end a button-shaped head or enlargement C. The stem or body portion A of the casing rises from the flat base, which latter has a short cylindric boss D on its under side.

Having described my invention, what I claim as new, and desire to secure by Letters Patent, is—

20 The design for a valve-case for pneumatic tires, substantially as herein shown and described.

ELTON W. McCASLIN.
